(57) **CLAIM**

The ornamental design for a double needle threader, as shown.

DESCRIPTION

FIG. 1 is a top perspective view of the double needle threader;

FIG. 2 is a bottom perspective view of the double needle threader;

FIG. 3 is a top plan view of the double needle threader;

FIG. 4 is a bottom plan view of the double needle threader;

FIG. 5 is a right side view in elevation of the double needle threader oriented as in FIG. 4;

FIG. 6 is a left side view in elevation of the double needle threader oriented as in FIG. 4;

FIG. 7 is a right end view in elevation of the double needle threader oriented as in FIG. 4; and,

FIG. 8 is a left end view in elevation of the double needle threader oriented as in FIG. 4.

The broken lines shown in the drawings depict portions of the article that form no part of the claimed design.
